UNITED STATES PATENT OFFICE.

GEORGE WALKER, OF NEWTON CENTER, MASSACHUSETTS.

MECHANISM FOR CONTROLLING THE LOCKS OF THE COMPUTING-NUMERALS IN A COMPUTING-MACHINE.

1,098,855.

Specification of Letters Patent. Patented June 2, 1914.

Application filed July 25, 1912. Serial No. 711,502.

To all whom it may concern:

Be it known that I, GEORGE WALKER, a citizen of the United States, and resident of Newton Center, in the county of Middlesex 5 and State of Massachusetts, have invented new and useful Improvements in Mechanism for Controlling the Locks of the Computing-Numerals in a Computing-Machine, of which the following is a specification.

This invention relates to computing machines, and particularly to typographical computing machines of the kind shown in Letters Patent of the United States No. 996,173, issued to me June 27, 1911, and consists in certain improvements upon, and 15 modifications of, the mechanism for operating the locks of the gear wheels which rotate the type wheels or number wheels, or otherwise actuate the computing numerals.

In the following description, and the drawings referred to herein, I describe and show only such parts of the computing machine as are necessary to a clear understanding of the improvements and modifications 20 which constitute the subject matter of the present application. For a description of the construction and operation of the machine as a whole, reference may be had to my said former patent, and especially to 25 the part of the specification beginning on page 30, line 64, of said patent, which describes those parts of the machine immediately associated with the subject of the present invention. For convenience I shall use 30 the same reference numerals as in my said former patent so far as they are applicable.

Referring to the accompanying drawings, which show a vertical, longitudinal, sectional view of that part of an adding machine containing the type wheels, type wheel gears, and mechanism for operating the same, to which the present improvement is applied, 1 represents one of the main gear 35 wheels for actuating the computing numerals, herein shown as carried by the type wheels 3; 11^A and 11^B represent respectively the pawl and pawl latch, together constituting a self-locking driving pawl, for rotating the gear wheel 1; 18 represents the 40 latch or lock normally engaging gear wheel 1; 18^A represents a piece pivoted on shaft 20, the lower arm of which, when swung downward, presses against latch 18, thereby setting the locking pawl 11^A into gear wheel 50 1; 18^B represents a pin mounted on the

upper arm of piece 18^A and engaging the tail of lock 18, to lift the lock 18 when piece 18^A is swung downward; 564 represents a shaft extending between the side frames of the machine, of which one is shown at B', 60 supporting a swinging cross bar or latch 566, normally urged upward by a spring 568; 567 represents a rod connected to and extending downward from latch bar 566; 577 represents a swinging arm journaled on a shaft 14, and shaped to strike the nose of latch 11^B thereby releasing pawl 11^A in any position to which it may be rotated with gear wheel 1; 570 is a rod hung on arm 577, and 572 is a spring tending to press arm 70 570 upward; and 560 is a three-arm bell crank lever, the turning of which pulls bar 33-36 to the left as viewed in the drawing. The parts thus far described are of substantially the same construction and perform the 75 same functions as described in my said former patent. It will be understood that there is a similar train of mechanism for each gear wheel 1, that is, for each column of the machine.

The bar 561, instead of being of the same construction as the corresponding part shown in my said former patent, is of the construction shown in the accompanying drawing, having the upper shoulder 561^A, 85 engaging the end of the upper arm of piece 18^A, which is extended far enough to project under said shoulder. Bar 561 also has the lower shoulder 561^B. There is a part 561 for each column, and said parts 561 are 90 mounted to slide vertically between the teeth of combs 719 and 719', which extend between the side frames of the machine, with their teeth pointing to the left as viewed in the drawing. Rods 565 and 565' 95 also extend between the side frames of the machine and hold the bars 561 in place in the combs. On the end of the upper arm of bell crank lever 560 is pivoted a latch 562^A, 100 engaging shoulder 561^B, and normally held in the position shown by spring 560'.

Shaft 717 extends between the side frames of the machine, its ends turning therein. Bell crank 716 is fastened solidly on shaft 717 inside of side frame B'. An arm (not shown) identical with the lower arm of bell crank 716 is fastened solidly on shaft 717 inside of the opposite side frame, and between said arm and the lower arm of bell crank 716 extends the rod 718. 110

569^A is a pin projecting from the lower end of arm 570 under bar 33-36.

Latch 18 is provided with a downwardly extending arm 18^C, which projects between the gear wheels 1, and into the path of swinging arm 577.

When a key is depressed, it will cause bell crank lever 560 to swing on its fulcrum as described in my said former patent, thereby 10 causing latch 562^A, acting on shoulder 561^B, to pull part 561 downward. The downward movement of part 561, through the upper shoulder 561^A which engages the extended upper arm of piece 18^A, swings piece 18^A 15 downward, thereby lifting lock 18 out of the gear wheel 1, and (by means of the lower arm of 18^A) setting the locking pawl 11^A-11^B into the gear wheel 1. At the completion of the action of piece 18^A, cross bar 20 566, acting as a latch, snaps into a notch in the end of the lower arm of 18^A, holding the lock 18 in its elevated or inoperative position. Upon the completion of the foregoing action, the latch 562^A will slip off the shoulder 25 561^B thereby disconnecting the bell crank lever 560 from part 561 and the mechanism which is operated by 561.

The continued depression of the key and the consequent swinging of bell crank 560, 30 brings the projection 33^A, on bar 33-36 (which moves toward the left actuated by bell crank 560) into engagement with rod 718, swinging bell crank lever 716, and pulling downward rod 567, thus removing the 35 latch bar 566 from the notched end of piece 18^A, and releasing the lock 18 so that it is free to be reset into gear wheel 1. At the same time when the projection 33^A actuates bar 718, it also engages pin 569^A, acting 40 through link 570 to pull arm 577 toward the left, and causing it to strike the nose of latch 11^B thus releasing the pawl 11^A, and simultaneously striking the arm 18^C on lock 18 and positively setting the lock 18 in 45 locked position in the gear wheel. The action of latch bar 566, which holds the lock 18 in elevated position, and the action of arm 577, which simultaneously disengages pawl 11^A and sets lock 18, are relatively so 50 timed that the lock 18 is released by latch bar 566 the instant before the arm 577 strikes arm 18^C to reset the lock 18 in the gear wheel.

With this construction it will be seen that 55 the relocking of the gear wheel 1 is in no way dependent on spring action but is effected positively by the key action at the end of each key operation. It will also be seen that at no time will the gear wheel 1 60 be free to rotate accidentally or improperly since it is always positively engaged either by lock 18 or by pawl 11^A. As described in my said former patent, the pawl 11^A begins to enter the teeth of gear wheel 1 before 65 the lock 18 is fully withdrawn therefrom.

and, conversely, when pawl 11^A is being disengaged from gear wheel 1 at the end of the stroke, the relation between arm 577 and arm 18^C is such that lock 18, positively actuated by said arms, will again begin to enter between the teeth of said gear wheel before pawl 11^A is fully withdrawn therefrom. Spring 19 is used as in my said former patent normally to hold said lock 18 in locked position, but in case of the failure of said spring for any reason to act properly, arms 18^C and 577 insure the positive resetting of the lock 18 quite independently of the spring.

I claim:

1. In a computing machine, a gear wheel for actuating the computing numerals, a lock normally holding said gear wheel against rotation, normally disengaged wheel-rotating mechanism to rotate said gear wheel, operating mechanism simultaneously to disengage said lock and engage said wheel-rotating mechanism with the gear wheel, and then to rotate said gear wheel, means to hold said lock in disengaged position during the rotation of the gear wheel, and means actuated by said operating mechanism adapted automatically and positively to reset said lock at the end of each rotation of said gear wheel.

2. In a computing machine, a gear wheel for actuating the computing numerals, a lock normally holding said gear wheel against rotation, normally disengaged wheel-rotating mechanism to rotate said gear wheel, operating mechanism simultaneously to disengage said lock and engage said wheel-rotating mechanism with the gear wheel, and then to rotate said gear wheel, means to hold said lock in disengaged position during the rotation of the gear wheel, and a single member actuated by said operating mechanism adapted automatically both to disengage said wheel-rotating mechanism and positively to reset said lock at the end of each rotation of said gear wheel.

3. In a computing machine, a gear wheel for actuating the computing numerals, a lock normally holding said gear wheel against rotation, normally disengaged wheel-rotating mechanism to rotate said gear wheel, operating mechanism simultaneously to disengage said lock and engage said wheel-rotating mechanism with the gear wheel, and then to rotate said gear wheel, means to hold said lock in disengaged position during the rotation of the gear wheel, and a swinging arm actuated by said operating mechanism adapted automatically both to disengage said wheel-rotating mechanism and positively to reset said lock at the end of each rotation of said gear wheel.

4. In a computing machine, a gear wheel for actuating the computing numerals, a lock normally holding said gear wheel

against rotation provided with an arm projecting inward beside said gear wheel, a normally disengaged driving pawl for rotating said gear wheel, operating mechanism adapted to disengage said lock, engage said driving pawl with said gear wheel and rotate said gear wheel, and a swinging arm actuated from said operating mechanism adapted to disengage said driving pawl from said gear wheel and also to strike the arm projecting from the lock, thereby positively swinging said lock into locked position.

5. In a computing machine, a gear wheel for actuating the computing numerals, a

pivoted lock normally holding said gear wheel against rotation having a tail piece by which the lock is disengaged from the gear wheel, an endwise movable bar having a shoulder near the top for actuating 20 said tail piece, another shoulder near the lower end of said bar, and a lever having a latch pivoted to its end to engage the last named shoulder and move said bar endwise.

Signed by me at Boston, Massachusetts, 25 this seventeenth day of July, 1912.

GEORGE WALKER.
